UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

METHOD OF FORMING BUTTONS AND THE LIKE.

Application filed March 19, 1923. Serial No. 626,126.

To all whom it may concern:

Be it known that I, RICHARD LESTER WILCOX, a citizen of the United States, residing at Waterbury, in the county of New Haven and State of Connecticut, have invented certain new and useful Improvements in Methods of Forming Buttons and the like, of which the following is a specification, reference being had therein to the accompanying drawings.

This invention relates to a new and improved method of forming buttons and the like, and refers more particularly to a type of button that is secured by means other than a thread.

It is the object of this invention, among other things, to produce a button of this character, and of an endless variety of shapes, from a single piece of metal, by tools that are simple in their construction and operation.

To these, and other ends, my invention consists in the method of forming buttons and the like, substantially as hereinafter shown and described.

Referring to the drawings, in which like numerals of reference designate like parts in the several figures;

Fig. 1 illustrates end and side views of a slug or blank from which the button is made;

Fig. 2 illustrates similar views of the blank after an operation thereon;

Fig. 3 illustrates similar views of the blank after an operation thereon subsequent to the one that produced the blank shown in Fig. 2;

Fig. 4 illustrates similar views of the blank after an operation thereon subsequent to the one that produced the blank shown in Fig. 3;

Fig. 5 is a sectional view of my improved button showing one of the conventional means for its attachment to a fabric or the like;

Fig. 6 is a fragmentary sectional elevation of one form of the tools in their relative positions after the formation of a blank as shown therein and illustrated in Fig. 2;

Fig. 7 is a similar view of one form of the tools utilized to shape the blank as shown therein and illustrated in Fig. 3; and

Fig. 8 is a similar view of one form of the

tools in their relative positions after the formation of the blank as shown therein and illustrated in Fig. 4.

In the drawings, 10 designates the blank, which is preferably cylindrical in form, cut from a wire rod or length, or it may be of cast metal if desired.

The blank 10 is presented to a set of tools, substantially as shown in Fig. 6, wherein 11 designates a die, and 12 a punch, within which is a relatively movable sleeve 14 of substantially the same diameter as the shank 17, as shown in Fig. 2. Within the sleeve is the supplemental punch 13 that is actuated in part by the spring 15 in a manner well known in the art. The opposite faces of the die 11 and punch 12 are shaped so that when in the relative positions, shown in Fig. 6, the head 16 of the button is formed therebetween upon one end of the blank, the other end of which forms the shank 17 and projects into the opening 18 in the punch 12. If the metal of which the blank is composed is too hard to permit the forming of the head 16 in one blow, the same may be subjected to such additional blows as may be requisite and as is common in the heading art.

The operations upon the blank performed by the tools, as shown in Fig. 6, are completed by the movement of the supplemental punch 13, which is projected into the end of the blank to form the opening therein, which is of substantially uniform diameter, with a rounded or other shaped bottom, as desired. After the withdrawal of the punches 12 and 13 and their associated parts, the blank is held against the face of the die 11 by the fingers 20, substantially as shown in Figs. 7 and 8. Thereafter a punch 21 with a conical recess 22 therein engages and cones the shank 17, at which time the outer end of the opening 19 therein is reduced in diameter, substantially as shown, and without reducing the shape or size of the bottom thereof, which opening is now substantially pear shaped, as shown in Figs. 3 and 7.

After the withdrawal of the punch 21, a punch 23, having a supplemental punch 24, engages the end of the shank 17, and by the application of pressure thereon reduces its length. During this operation, the inner reduced end 25 of the punch 24 projects

into the opening 19 and determines the size and shape thereof at its outer end, the shoulder 26 on this punch 25 forming a depression 27 in the end of the shank substantially concentric with the opening 19, the inner end of which is now a pocket 28 of very much larger diameter than that portion 29 of the opening leading therefrom.

In the drawings, the head 16 is shown as 10 being cylindrical, but it may be of any desired shape. This has not heretofore been possible, and in addition thereto, letters, figures, symbols or the like, may be formed thereon by making provision therefor upon 15 either the die or the punches or both.

In Fig. 5 the button is shown as attached to a fabric 30 or the like, by a tack 31, which passes through the fabric, and the pointed end 32 thereof engages the end of the pocket 20 28, which acts as an anvil for said point, which is turned upon itself and substantially fills the pocket and cannot readily be withdrawn therefrom.

Having described my invention, what I 25 claim as new and desire to secure by Letters Patent, is:—

1. The herein-described method of making buttons, which resides in subjecting a

blank to endwise pressure to form a head, and a hollow shank, then in subjecting the 30 blank to lateral pressure thereby to taper the free end portion of the shank so as to cause the interior thereof to be of substantially pear-shape, and finally in subjecting the shank to endwise pressure to reduce the 35 length of the shank and in arresting the inward flow of the metal to reduce the diameter of the outer portion of the shank interior.

2. The herein-described method of making buttons, which resides in subjecting a blank to pressure to form a head and a hollow shank, then in subjecting the blank to further pressure thereby to taper the free end portion of the shank so as to cause 40 the interior thereof to be of substantially pear-shape, and finally in subjecting the blank to still further pressure to reduce the length thereof and in simultaneously arresting the inward flow of the metal to reduce 45 the diameter of the outer end portion of the shank interior.

In testimony whereof, I have hereunto affixed my signature.

RICHARD LESTER WILCOX.
